DESIGN FOR A TABLE

Bernard R. Glukes, Los Angeles, Calif.

Application March 31, 1945, Serial No. 118,806

Term of patent 3½ years

(Cl. D33—14)

To all whom it may concern:

Be it known that I, Bernard Raphael Glukes, a citizen of the United States, residing at Los Angeles, in the county of Los Angeles and State of California, have invented a new, original, and ornamental Design for a Table, of which the following is a specification, reference being had to the accompanying drawing, forming part thereof.

The single figure in the drawing is a perspective view of a table showing my new design.

I claim:

The ornamental design for a table, as shown.

BERNARD R. GLUKES.
